UNITED STATES PATENT OFFICE.

JOHN E. MITCHELL AND DENNIS PARKS, OF ST. LOUIS, MISSOURI.

HULL-BOARD CONSTRUCTION.

1,348,031.

Specification of Letters Patent. Patented July 27, 1920.

Application filed March 29, 1919. Serial No. 285,996.

To all whom it may concern:

Be it known that we, JOHN E. MITCHELL and DENNIS PARKS, citizens of the United States, residing in the city of St. Louis and

5 State of Missouri, have invented new and useful Improvements in Hull-Board Construction, of which the following is a specification.

This invention relates to improvements in 10 boll breaking and cotton separating machines of the single hull board type, and has for its general object the provision of improved means for preventing congestion in the working chamber of the machine.

15 In a companion application, having the same object in view, we have shown a construction whereby, in the operation of the machine, the hull board is periodically moved to widen the opening between its lower edge 20 and the saw cylinder, to permit the free escape from the working chamber of the products that have accumulated therein, together with mechanism coördinating the movement of the hull board with the feeding mechanism, to the end that the feed of bolls and 25 cotton to the machine may be stopped before the hull board is moved to the discharge position, and the hull board be restored to its normal position before the feed is resumed.

30 In the present case we retain the principle of periodically moving the hull board to discharge the contents of the working chamber, but in place of coördinating the movement of the hull board with the feeding mechanism, we provide for discharging the 35 contents of the working chamber, when the hull board is moved for this purpose, into a separate compartment from that receiving the normal discharge of the working chamber, so that any unopened bolls or cotton particles discharged from the working chamber may be returned to the main battery of the machines for retreatment, or else be sent to a recleaning machine.

40 The invention, therefore, resides in a boll breaking and cotton cleaning machine affording a working chamber in which the separating mechanism operates: a hull board, the lower end of which defines the size of an opening past a member of the separating mechanism to permit of the continuous discharge of hulls and waste from the working chamber; means for periodically moving the hull board to widen said opening to permit 45 of discharging accumulated products from the working chamber, and means operating

simultaneously with the movement of the hull board to shunt the products so discharged from the working chamber to a different location, or compartment of the machine, from that receiving the normal discharge from the working chamber.

50 Stated more in detail the invention resides, in its preferred embodiment, in a machine of the class described having two separate compartments, and a movable valve connected to the hull board, which, in the operative position of the hull board, causes the normal discharge from the working chamber of the machine to pass to one compartment, and, when 55 the hull board is moved to discharge the contents of the working chamber, is moved to a position to cause the discharged products to pass to the other compartment.

55 In the accompanying drawings:

Figure 1 is a view in side elevation of a machine constructed according to our invention; and

Fig. 2 is a cross sectional view thereof.

Referring now to the drawings, the numeral 1 indicates, generally, the casing of the machine, in which are mounted for rotation in the respective directions indicated by the arrows, feed rolls 2, 3; a boll breaking cylinder 4, a saw cylinder 5, a kicker 85 roll 6, a doffer roll 7 and conveyers 8, 9. Extending transversely of the bottom part of the machine is a partition 10 extending between said conveyers and providing compartments 11 and 12 for receiving products 90 from the working chamber, as hereinafter explained. The upper part of the machine provides a hopper 13 into which the gathered bolls are thrown and the raw product is fed by the feed rolls 2, 3 into a chamber 95 14, in which the boll breaking cylinder 4 operates, the latter serving to break apart the bolls and discharge the mixed cotton and hulls resulting through an outlet 15 into a working chamber 16. In this working chamber the cotton is caught up by a saw cylinder 5 and carried beneath the kicker roll 6, which operates to knock back hull particles carried up by the cotton. The cotton carried through by the saw cylinder 100 105 is removed by the doffer roll 7 and discharged through an outlet 17. The numeral 18 indicates a screen forming one wall of the boll breaking chamber and through which a certain amount of dirt, dust and the like, will be separated from the cotton by 110 the agitation occurring in the boll breaking

chamber. The numeral 19 indicates the hull board, which occupies an inclined position relative to the saw cylinder and operates, as well understood, to cause the mixed 5 cotton and hulls to be fed downward toward the saw cylinder, so that the cotton may be caught up by the same. The lower end of this hull board is located at a distance from the saw cylinder to provide a 10 passage 20, through which the hull particles, trash, and the like, may escape and fall into the compartment 11 to be conveyed out of the machine by the conveyer 8, when the parts are in the position shown by the full 15 lines in Fig. 2. In the companion application referred to we have set forth the objections to the use of a single stationary hull board, and have disclosed the use of a movable hull board, whereby the working chamber 20 may be periodically emptied to free it from accumulated products. The same principle of operation is retained in the present case, and in addition we have embodied in the hull board construction means 25 for shunting the discharged products, when the working chamber is emptied, to a different part of the machine from that receiving the normal discharge from the working chamber. This construction will now be 30 described.

The hull board 19 is pivotally mounted at its upper end, as indicated at 21, between the side members of the casing, so that its lower end may be moved toward and from 35 the saw cylinder 5. Located beneath the hull board is a cam roller 22 provided in its periphery with a recess 23 affording a cam surface 24. Secured on the under side of the hull board is a plate 25 having a 40 rearwardly projecting lug 26 which, in the normal position of the hull board shown in full lines in Fig. 2, rests upon the surface of the roller 18, and, when the recess 23 passes under said lug, falls into said recess, 45 thereby allowing the hull board to swing away from the saw cylinder and automatically widen the opening 20. As the cam continues to revolve, the cam surface 24 engages the lug 26 and gradually raises the hull board until the lug again rests on the periphery of said roller. Formed integral with the plate 25, or otherwise secured to the hull board 19, is an arm 27, projecting a considerable distance below the lower end 50 of said hull board. Pivots connected at 28 to the lower end of this arm is one end of a rod 29, the other end of which is pivotally connected at 30 in a bearing formed on a plate 31 secured on one side of a vertically-disposed valve 32. The valve 32 extends transversely of the machine from one side wall to the other, and is preferably tapered from its lower to its upper edge, the lower edge being rounded to work in a cup-shaped recess 33 formed on the upper edge 55 60 65 70 75 80 85 90 95 100 105 110 115 120 125 130

of the partition 10. The pivot 30 is located below the vertical center of the valve 32, and as the lower end of the arm 27 will have a greater arc of movement than the lower edge of the hull board 19, these combined factors insure the movement of the upper edge of the valve 32, for a greater distance than the bottom of the hull board when the lug 26 falls into the recess 23, the relative positions of the parts, when the hull 70 board swings open, being shown by the dotted lines in Fig. 2. Normally, the upper edge of the swinging valve 32 rests against the edge of a foraminous sheet 34 partly surrounding the bottom portion of the saw 80 cylinder, and thereby closes communication between the passage 20 and the compartment 12, so that the hull particles passing through said passage will be compelled to fall into the compartment 11. In the open 85 position of the hull board, shown by dotted lines, the upper edge of the swinging valve will be thrown outward, or in the opposite direction, beyond a vertical line passing through the passage 20, or, in other words, beyond the lower edge of the hull board 19, so that any products passing through the widened space between the hull board and the saw cylinder will be directed by the valve into the compartment 12. 95

In the operation of the machine, a certain number of bolls will escape from the boll-breaking chamber through the passage 15 without being broken apart by the cylinder 4, and as these unopened bolls are too large 100 to pass through the opening 20, in the operative position of the hull board, they gradually accumulate in the working chamber and in time will cause a congestion 105 therein, if some means be not provided for getting rid of them. This object of preventing congestion in the working chamber is accomplished by periodically discharging the contents of the working chamber by the movement of the hull board described. 110 The bolls discharged into the compartment 12 will be discharged from the machine by the conveyer 9, and may be conducted to a separate recleaning machine or back to the main battery of the machines on the gins. 115

The cam roller 22 is mounted on a rod 35 projecting through the casing at one side and having secured thereon a ratchet wheel 36. The shaft 37 of the saw cylinder also projects through the same side of the casing as the rod 35, and is provided with a crank-pin 38 on which is pivotally mounted a hub 38^a having an integral socket-member 38^b and an integral crank arm 39 which has pivotally mounted on its outer end, at 40, two ratchets, 41 and 42, respectively, connected by a spring 43. In the rotation 120 of the shaft 37 the ratchets 41 and 42 will be operated by the arm 39 to alternately pull and push the ratchet wheel 36 to cause them 125 130

to rotate and thereby rotate the cam roller 22. The shafts 44 and 45 of the feed rolls 2 and 3 also project through the same side wall of the casing as the rod 35 and shaft 37, and have secured on their projecting ends gears 46 and 47, respectively, which are in mesh with each other. Secured on the end of the shaft 44 is a ratchet wheel 48, which is adapted to be actuated by a ratchet 10 49 pivotally mounted on the upper end of an arm 50 of a bell-crank lever 15, which is pivotally mounted on the end of the shaft 45. A second arm 52 of this bell-crank lever is provided on its end with an apertured lug 15 53, through which extends loosely the upper end of a pitman rod 54, the upper end portion of which is screw-threaded to receive adjusting nuts 55, and below the lug 53 is provided with a bumper 56, which is pivotally mounted at 57 on a block 58 secured on the pitman rod 54. The lower end of the pitman rod is secured in the socket-member 38^b, previously referred to. As the shaft 37 revolves the crank pin 38 will cause 20 the pitman rod 54 to be alternately raised and lowered. In its upward movement the bumper 56 will engage the lug 53 and rock the bell-crank lever 51 and thereby move the ratchet 49 backward over the teeth of 30 the ratchet wheel 48. As the pitman rod moves downward the lower adjusting nut 55 will engage the lug 53 and thereby rock the bell crank lever in the opposite direction causing the ratchet 49 to rotate said ratchet 35 wheel, which in turn will result in rotating the ratchets 41 and 42 through the medium of the gears 46 and 47. By turning the bumper 56 downward on its pivot 57, so that it will not engage the lug 53, the operation 40 of the feed rolls can be discontinued at any time without otherwise stopping the operation of the machine.

It will be seen that in the present arrangement the feed is on continuously, and as the 45 dumping operation, effected by the movement of the hull board, occurs at each revolution of the cam shaft without the feed being shut off, it is obvious that some cotton of value will be dumped along with the bolls. 50 To prevent the waste of cotton which would otherwise occur if this discharged product were sent to the conveyer 8 to be conveyed to the hull pile, we provide the construction described, whereby the product discharged 55 in the dumping operation is maintained separate from the hulls and waste normally discharged from the working chamber. It will be understood that in the normal position of the parts shown in full lines in Fig. 60 2, the space 20 is wide enough to permit the free discharge of the separated hulls from the working chamber without permitting escape of any cotton of value.

We claim:—

65 1. A boll breaking and cotton separating

machine affording a working chamber for receiving the mixed cotton and hulls to be separated and having an outlet for hulls, cotton separating mechanism operating in said chamber, and means for periodically 70 discharging accumulated products from said working chamber in separated relation with respect to the hulls normally discharged therefrom.

2. A boll breaking and cotton separating 75 machine affording a working chamber for receiving the mixed cotton and hulls to be separated and having an outlet for hulls, cotton separating mechanism including a saw cylinder operating in said chamber, a 80 hull board coöperating with said saw cylinder, the bottom of which defines the size of an opening past the saw cylinder for the escape of hulls, means operating periodically to move said hull board to widen said 85 opening to discharge accumulated products from said chamber, and means operating to separately deliver such discharged products from the hulls normally escaping through 90 said opening.

3. A machine according to claim 2, in which the separate delivery of the products is effected by a swinging valve connected to the hull board and movable therewith to provide different paths of discharge for the 95 products of the working chamber in the operative and discharge positions of the hull board, respectively.

4. A machine according to claim 2, in which the separate delivery of the products 100 is effected by a swinging valve connected to the hull board in such manner that the movement of the free end of the valve will be multiplied as compared with the movement of the lower end of the hull board, so 105 that said valve will be moved to provide different paths of discharge for the products of the working chamber in the operative and discharge positions of the hull board, respectively. 110

5. A machine according to claim 2, having in its bottom portion two compartments, and in which the separate delivery of the product is effected by a swinging valve adapted to be positioned to open a path of 115 discharge from the working chamber to either of said compartments and to close it to the other, and in which said valve is positioned by a member projecting downwardly from the hull board and pivotally 120 connected to said valve nearer its pivot than its free end, whereby the movement of the free end of the valve, caused by the movement of the hull board, will be multiplied 125 as compared with the movement of the lower end of the hull board.

6. A boll breaking and cotton separating machine affording a working chamber, cotton separating mechanism operating therein including a saw cylinder, a pivotally 130

mounted hull board, the lower end of which defines the size of an opening past said saw cylinder for the discharge of hulls, said hull board being periodically movable in the 5 operation of the machine to widen said opening to discharge accumulated products from the working chamber, a vertically-disposed, swinging valve located below said opening and pivotally connected with said 10 hull board, whereby in the movement of

the latter the upper end of said valve will be turned to one side or the other with respect to said opening to provide different paths of discharge according as the hull board is in its normal or discharge position. 15

In testimony whereof we have hereunto set our hands.

JOHN E. MITCHELL.
DENNIS PARKS.
